HOUSING FOR COMPUTER INTERFACE UNIT

Charles J. Ortega, Van Nuys, and Frederic L. Naff, Jr.,
Los Angeles, Calif., assignors to Computer Transmis-
sion Corporation, Los Angeles, Calif.

Filed Mar. 23, 1970, Ser. No. 22,016

Term of patent 14 years

Int. Cl. D14—02

U.S. Cl. D26—5

FIG. 1

FIG. 2

FIG. 3

FIG. 1 is a front perspective view of a housing for a computer interface unit showing our new design;

FIG. 2 is a left side elevational view;

FIG. 3 is a rear perspective view thereof.

The right side of the design is substantially identical with the left side shown in FIG. 2.

We claim:

The ornamental design for a housing for computer interface unit, as shown and described.
